UNITED STATES PATENT OFFICE

136,167

DESIGN FOR A DOLL OR SIMILAR ARTICLE

Joseph Rubin, New York, N. Y.

Application June 2, 1943, Serial No. 110,348

Term of patent 7 years

To all whom it may concern:

Be it known that I, Joseph Rubin, a citizen of the United States, residing in New York, New York, have invented a new, original and ornamental Design for a Doll or Similar Article, of which the following is a specification, reference being had to the accompanying drawing, forming part thereof.

Figures 1 and 2 of the drawing are, respectively, front and side views of a doll showing my new design.

I claim:

The ornamental design for a doll or similar article, substantially as shown.

JOSEPH RUBIN.
